UNITED STATES PATENT OFFICE.

RICHARD HENRY GULLEFORD, OF ST. ALBANS, CHRISTCHURCH, NEW ZEALAND.

PEDAL FOR BICYCLES AND THE LIKE.

1,109,585.

Specification of Letters Patent.

Patented Sept. 1, 1914.

Application filed May 5, 1914. Serial No. 836,394.

To all whom it may concern:

Be it known that I, RICHARD HENRY GULLEFORD, a subject of the King of Great Britain, residing at 28 Oxley street, St. Albans, Christchurch, in the Dominion of New Zealand, have invented new and useful Improvements in Pedals for Bicycles and the like, of which the following is a specification.

10 This invention relates to pedals for bicycles, tricycles and the like, its object being to provide a construction which, by reason of its conformity to the anatomy of the foot, will give increased comfort to the rider.

15 As hitherto constructed the two bars which constitute the tread of the pedal, have been disposed parallel with the crank-pin. The flexing of the foot at the joint between the instep and the toes however, occurs in 20 an oblique direction, the result being that, in the case of a pedal of the abovementioned form, the strain is thrown largely upon one portion of the foot and so causes unnecessary fatigue to the rider and occasions considerable wear both to the boot and the tread-bars of the pedal.

It is the object of the present invention therefore to provide a construction whereby the pressure of the pedal will be distributed 30 evenly across the full width of the foot.

In carrying this object into effect the invention consists in arranging the rearmost tread-bar parallel with the line of the said flexure of the foot when the latter is in place 35 upon the pedal.

In order that the nature of the invention and its construction may be fully understood, reference will now be made to the accompanying sheet of drawings in which:—

40 Figure 1.— is a plan view of a pedal constructed in accordance with the present invention, Fig. 2.— is a similar view showing a reversible form of the pedal, and, Fig. 3.— is again a similar view illustrating an alternative construction for that of Fig. 1.

45 In its general construction the pedal adheres to the well-known practice comprising a sleeve 1 revolvably mounted upon the crank-pin 2 by means of ball-bearings or otherwise, such sleeve being provided at either end with webs 3 between which tread-bars 4 and 5 extend.

According to the present invention the rearmost tread-bar 5, instead of being paral-

55 lel with the crank-pin as heretofore, is disposed obliquely; that is to say it extends from its outer end at an angle with the crank-pin in an inwardly and forwardly direction so as to lie parallel with the line of the aforementioned flexure of the foot. 60

In the form shown in Fig. 1, the forward tread-bar 4 is arranged in the customary way, parallel with the crank-pin 2, while in that of Fig. 3, such tread-bar 4 is parallel with the rearmost tread-bar 5, or approximately so. In both these forms however it will be seen that, to secure the advantages of the invention, it is necessary for the pedal to be placed the correct way up. It will be seen however that owing to the particular 70 disposal of the weight in both these forms, the pedal when not in use will hang with the tread-bar 5 downward, from which position it will be brought naturally into the required working position by the pressure of 75 the foot upon the tread-bar 4. In the form shown in Fig. 2, however, both the tread-bars 4 and 5 are disposed at the said angle so as to converge inwardly, by which arrangement the pedal may be reversed, that 80 is to say, used either way up while still preserving the desired angularity of the rearmost tread-bar. The invention is not however confined to any specific disposition of the forward tread-bar, but includes within 85 its scope any arrangement of the pedal whereby the said angularity of the rearmost tread-bar is obtained. It is obvious also that the present invention applies equally to whatever type of tread-bars may be employed, whether of the plain metal, "rat-trap" rubbered or other form or composition. 90

I claim:—

A pedal for bicycles, and the like, having 95 its rearmost tread-bar disposed at an angle with the crank-pin in an inwardly and forwardly direction from the outer extremity of such tread-bar, substantially as and for the purpose set forth.

100 In testimony whereof I have signed my name to this specification in the presence of two subscribing witnesses.

RICHARD HENRY GULLEFORD.
